NESTING PAPER CAN

William F. Goez, Keokuk, Iowa, assignor of one-half to Iowa Fiber Box Company, Keokuk, Iowa, a corporation of Delaware, and one-half to South West Box Company, Sand Springs, Okla., a corporation of Delaware

Application March 23, 1932, Serial No. 600,797

2 Claims. (Cl. 229—5.5)

This invention relates to containers and, among other objects, aims to provide an improved reinforced container which may be used satisfactorily in lieu of the metal cans in which ice cream is packed for the retail trade, the particular object being to provide a paper can which may be nested, for economy in shipping and in storage space, yet may be tightly closed at the top by a flanged cover or cap and will have an unusually strong and leak-resisting bottom construction.

This is a companion application to application Ser. No. 600,798, filed March 23, 1932.

In the drawing, showing a preferred embodiment of the invention:—

15 Fig. 1 is a side elevation of the improved container;

Fig. 2 is a horizontal sectional view taken on line 2—2 of Fig. 1;

20 Fig. 3 is an enlarged, vertical, fragmentary, sectional view of the upper part of the container;

Fig. 4 is an enlarged, vertical, fragmentary, sectional view of the lower part of the container;

Fig. 5 is a horizontal sectional view taken on line 5—5 of Fig. 4; and

25 Fig. 6 is a fragmentary view of the lower portion of the blank from which the container is made.

Various kinds of paper containers are in use for holding small quantities of ice cream and other foodstuffs but so far as I know, there are no satisfactory paper cans capable of holding one to ten gallons of ice cream or other semi-solids which can withstand the usage which such containers receive in shipping, trucking and refrigerating. The present invention provides an improved large paper can which meets all of the requirements of the trade and which may also be nested so as to require a minimum of space during shipment or when stored empty.

30 Referring particularly to the drawing, there is shown a paper can having a frusto-conical body portion 10 of slight taper, the larger end being at the top of the container, so that the empty containers may be nested. The body is conveniently formed by wrapping a sheet of fiber board around a tapered mandrel and securing the overlapping edges together by suitable stitches 11.

35 In order that a cap or cover (not shown) may be frictionally secured on the container, and at the same time to provide a shoulder for engagement by lifting devices, the upper portion 12 of the body is made cylindrical, as shown in Fig. 3, and a collar 13 is secured on the cylindrical portion. This collar is preferably made by winding 40 two layers of fiber board spirally in opposite di-

rections on a forming mandrel. The spiral winding is so accomplished as to provide abutting but not overlapping edges, as shown in Fig. 1, to insure a nearly true cylindrical outer surface. The collar is preferably secured on the container by glue or the like. As the outer surface of the collar is cylindrical, this permits a flanged cap (not shown) to be frictionally held on the container, which would not be possible if the container were tapered at the top. Also, the collar materially 45 strengthens the container. The lower edge of the outside layer 14 of the collar provides a shoulder under which a can lifter (not shown) may be engaged, the width of the outside layer being such that it conveniently accommodates 50 present day can lifters, so that the can may be lifted out of a refrigerating compartment or truck body. The width of the inner layer 15 may be the same as the outer layer 14 but is preferably greater so as to provide additional 55 reinforcement. At the same time, it is not so wide as to become wedged in the next lower container when nested, which would make the nested containers difficult to separate.

60 The blank from which the container is made, a portion of which is shown in Fig. 6, is provided at its lower end with a series of integral tongues 16 each tapering to a point. The lower end of the blank is adapted to be bent on the dotted lines 17 and 18 to form a kind of a bead for 65 strengthening the bottom of the can. That portion of the blank between lines 17 and 18 is bent inwardly and upwardly on line 18 to form an inner wall 19, which is spaced from the outer wall, as shown in Fig. 4, and the tongues are then bent 70 inwardly on line 17 forming an inner circumferential flange. To further strengthen the container, an annular collar 20, formed of several layers of spirally wound paper material is secured 75 between the inner and outer walls by glue. The bottom of the container is made of at least two disks of fiber board 21 and 22, the disk 21 being above the flange formed by the tongues 16 and glued thereto. The other disk 22 is glued at its 80 marginal portion to the undersides of the tongues 16 and at its central portion to the underside of disk 21, as will be clear from Fig. 4. The diameters of the disks are such that the disk 21 can only be inserted as far as its final position by a 85 press fit and thus very tightly engages the inner wall of the container, while the edge of disk 22 is likewise pressed against the inner wall 19. The entire container is preferably coated on the 90 inside with paraffin or other suitable moisture proof material so that the containers are particu- 95

larly adapted for use with ice cream, butter, lard or other similar materials. The paraffin may be coated in accordance with the process described in the Shofer application Ser. No. 586,630, filed 5 January 14, 1932, and assigned to the assignees of the present application.

10 The reinforcing collars at the top and bottom of the container, and the glued disks and ring at the bottom, together with the bead, result in a strong and durable container, which will withstand much abuse. The tapered side walls permit the containers to be nested, and thereby occupy less space in shipping and storing.

15 Obviously, the present invention is not restricted to the particular embodiment thereof herein shown and described.

What I claim is:—

1. A nesting container comprising, in combination, a frusto-conical body made from a single 20 sheet of paper whose edges are secured together; the lower portion of said body being bent inwardly and upwardly to provide a relatively narrow inner annular wall; a reinforcing paper collar between the inner and outer walls; a plurality of

tongues integral with and extending inwardly from the upper end of the inner wall in substantially a horizontal plane with the top of the collar; a paper disc press-fitted inside the body at the bottom and covering said tongues and collar; a second paper disc press-fitted within the reinforced annular wall outside the tongues and being in contact in the center with the first mentioned paper disc.

2. A paper can comprising, in combination, a 10 side wall formed of a single sheet of paper overlapped and united; the lower edge of said wall being bent inwardly and upwardly and finally 15 radially inwardly to form a bead and an inturned flange; a paper ring inserted between the upwardly bent portion of said wall and the lower edge portion thereof to reinforce the bead internally; and a pair of paper disks, one outside, the other inside, with the inturned flange between them; said disks being secured by a press fit to 20 said wall and by glue to each other and to the inturned flange, thereby forming a bottom secured to the side of the wall.

WM. F. GOEZ.
